UNITED STATES PATENT OFFICE.

JACOB STIRISS, OF NEW YORK, N. Y., ASSIGNOR TO INTERNATIONAL TICKET COMPANY, OF NEWARK, NEW JERSEY, A CORPORATION OF NEW JERSEY.

TICKET DELIVERER.

Application filed December 13, 1921, Serial No. 522,180. Renewed July 17, 1923.

To all whom it may concern

Be it known that I, JACOB STIRISS, a resident of the city, county, and State of New York, and a citizen of the United States, 5 have invented certain new and useful Improvements in Ticket Deliverers, of which the following is a specification.

This invention relates to ticket deliverers, and more especially to dispensers of tickets 10 in limited quantities and its object is to store a quantity of tickets and render one accessible by having its end protrude so as to be grasped by the party desiring the same to enable him to remove it, and at the same 15 time draw another ticket out so far that it may be withdrawn by the next party. Another object of the invention is to sound an alarm as the ticket leaves the machine so that an attendant may see that the party 20 desiring the ticket takes only one.

These and other objects of this invention are more fully described in the following specification, set forth in the claims, and illustrated in the accompanying drawings, 25 wherein:

Figure 1 is a side elevation of a ticket deliverer embodying my invention.

Fig. 2 is a central vertical sectional view of the same.

Fig. 3 is a sectional view through the casing on the line 3—3 of Fig. 4.

Fig. 4 is a front elevation partly in section.

Fig. 5 is a plan view of the feed roller.

In cafés and dining rooms where it is the custom to supply the patron with tickets or checks in which the amount of purchases is punched, fraud is possible where said patron takes two tickets and has different purchases 40 punched therefrom and offers but one of the smaller check for payment.

It is therefore found desirable to furnish the patrons with but one ticket and as the cost of a personal distributor would be considerable, the present invention is designed to fill all the requirements for single delivery.

At the front side of an upright case 10 are two knurled rollers 11 and 12, the shaft of 50 the former journaled in the case, while lower roller 12 is journalled in movable bearings 13 with stems 14 playing in boxes 15 and having springs 16 to force the roller 12 against roller 11, yet capable of movement 55 away from the same.

These two friction rollers are geared together by gear wheels 17 and 18 and meshing with the latter is an idler 19 that drives a toothed feed roller 20 through the gear wheel 21 so that all of these rollers rotate 60 in unison.

The upper part of the casing comprises a chute 22 in which is fitted a weighted follower 23 with studs 24 that play in the vertical slots 24' and direct the follower 65 towards the feed roller 20, but the slots 24' terminate so far above the roller that the follower will not injure the roller when the chute is empty.

The chute 22 is adapted to be filled with 70 the tickets or checks to be delivered, and the follower presses them down on the feed roller 20 as shown in Figs. 2 and 3 and the front and rear lower ends of the chute are inclined, as at 25 and 26, so as to throw the 75 stack of tickets outward. The inclined wall 25 is a slide that may be adjusted up or down and held at any desired height by the set screws 26 playing in slots in said slide while the inclined wall 26 is a part of the 80 casting of the base 27.

The machine is ready for operation when a check 28 protrudes, as shown in Figs. 2 and 3, affording access to the party desiring the same, and as the check is pulled out the 85 rollers 11 and 12 are put in motion and the toothed roller 20 caused to move in unison by the gear wheels 19 and 21. The removal of said check also aids in the rotation of roller 20, but when the check is removed 90 from the influence of the teeth of this roller, they will then engage the next check above the one being removed and start that check forward. At this time about three-fourths of the ticket or check is protruding from 95 the opening at the front of the machine, while the remaining portion is accompanied by the next check or ticket, and two are moving together until the first check leaves the rollers entirely and they are then at rest. 100 The second check now protrudes about a quarter of its length beyond the opening to be grasped by next patron.

This process will continue so long as the 105 checks are being pulled.

The engagement of the second check between the rollers 11 and 12 will depress roller 12 and cause a stud 29 on one of its bearings to lower the short arm 30 of a hammer lever 31 pivoted at 32 and drawn by the 110

spring 33 towards the gong 34. The proportion of leverage being so slight at the short end of this lever that the removal of the forward check will cause the bearing to ascend and cause the hammer 35 to strike the gong and signify to the attendant that a check had been removed to enable him to prevent the party from getting a second one.

The back of the case may be a door 36 10 for the insertion of a supply of checks and provided with a window 37 to detect a failing supply and a counter 37' may be attached to one side of the machine and operated with each rotation of the wheel 21 15 so that a record of the delivery of the tickets may be kept.

The object of the inclined faces 25 and 26 are to break any adhesion of checks, and at the same time to guide the front edge of 20 the check into the slot 25', the latter being adjusted to allow the entry of only one check above the one that is being pulled.

As shown in Fig. 5, it will be seen that the spurs 201 on the roller 20 are not only sharp pointed, but staggered so that if the first tooth should injure the paper the next tooth or its successors will find a place in the paper to connect with it and feed it out. These spurs 201 occupy only about a third 30 of the circumference or about enough to give the second check its start.

It will be seen by Figs. 2 and 3 that the tickets in the chute are supported by the friction wheel 20 and its spurs, and that the latter are effectually engaged when rotating 35 in the direction of the tickets.

It is obvious that the details of the device may be otherwise arranged without departing from the essential features above described, or from the scope of the appended 40 claims.

What I claim is:

1. In a ticket deliverer, the combination

of a chute having a slotted bottom and an outlet, an adjusting gate at the outlet, a 45 roller having spurs playing in the slotted bottom and adapted to engage a ticket thereon, a frictional roller journaled at the outlet, a second frictional roller co-operating with the first, spring-pressed journals for 50 the second roller to cause it to engage the first roller, a bell, a hammer carried by a lever and adapted to be operated by the journals when they move with their roller, and gear wheels connecting the rollers and 55 adapted to cause the roller with spurs to advance a ticket when a preceding ticket is pulled through the frictional rollers.

2. In a ticket deliverer, the combination 60 of a chute having a deflected lower end terminating in an outlet, friction rollers at the outlet, yielding bearings carrying one of the rollers, means operated by the rotating of the rollers by a passing ticket to advance a new ticket, a bell and a hammer connected 65 with the yielding bearings and adapted to be raised by the presence of two tickets between the rollers and released when one of the tickets is removed.

3. In a ticket deliverer, the combination 70 of a chute, friction rollers adjacent the same and adapted to be rotated by an ejected ticket, deflected walls at the lower end of the chute and inclined towards the rollers, a spur wheel adapted to move a superimposed 75 ticket forward when the lower ticket is pulled from between the rollers, gearing connecting the rollers with the spur wheel, an alarm, and means connected with the rollers for setting the alarm when two tickets 80 are between the rollers and sounding said alarm when one of the tickets is removed.

In testimony whereof I hereunto affix my signature.

JACOB STIRISS.
